THROUGH BEAD ATTACHING HOOK

Benjamin Nord, Bayside, N. Y., assignor to
 Whitney Metal Products Corp., New York, N. Y.,
 a corporation of New York

Application April 6, 1932, Serial No. 603,477

6 Claims. (Cl. 108—29)

The present invention relates to gutter hangers in general, and particularly to gutter bead attaching means associated with hangers of the "circle" type, and forms a continuation in part 5 of my co-pending application for Eaves trough hanger, Ser. No. 584,639, filed January 4, 1932, in which latter lever-operated bead-attaching means are described and illustrated, similar to those treated in the present application.

10 The prime object of this invention is to provide gutter bead attaching means, adapted to be adjustable to various sizes of gutters or gutter beads, and including means for preventing the bead attaching element from moving inwards, that is, 15 in the direction towards the gutter.

This and further objects will become more readily apparent from the following description, in connection with the accompanying drawing, forming a part of my disclosure, but which by no 20 means are intended to limit me to the actual showing, and in which

Fig. 1 illustrates a gutter bead attaching element in one of its forms, ready to engage a gutter bead.

25 Fig. 2 is the same attaching element in its bead-engaging position.

Fig. 3 is a side elevation of a modified form of a gutter bead attaching element.

Fig. 4 is an end elevation thereof.

30 Fig. 5 is a detail view of parts of this modified form.

Fig. 6 illustrates another modified form of my bead attaching element, and

Fig. 7 is still another form of my bead attach- 35 ing element.

Referring to Figures 1 and 2, numeral 10 denotes the outer end of a "circle" type gutter hanger provided with a hook-shaped end 11 and a seat 12 for the gutter hanger bead 13, the latter forming the outer edge of gutter 14. Seat 12 serves for rolling up and supporting bead 13, while being secured by my attaching element.

In these illustrations my attaching element is composed of a lever 15, which is hinged at 16 to the hook-shaped enlargement 11 of circle 10, and a hook member 17 provided with a hook-end 18 and attaching end 19, the latter provided with a slot 20, through which passes rivet 21 secured to lever 15. The portion of the lever in which rivet 21 is secured is raised, as indicated at 22.

To pivot 16 of the lever there is also secured a short angle 23, which serves as stop for hook member 17 when the latter is in its bead-engag- 55 ing position. Lever 15 is preferably equipped

with a lock provision 24, adapted to engage a depression 25 arranged in the circle.

When the trough is to be secured to the hanger, lever 15 is moved from its open position of Figure 1 to its closed position of Figure 2, whereby 60 rivet 21 is drawn down into slot 20. The pull exerted by lever 15 causes rivet 21 to slide downwards into an ever-increasing forcible engagement with the tapered edges of slot 20, whereby hook member 17 is caused to bear against bead 65 13 of the gutter. As the lever approaches its closing position, the bead is not only forced tightly down against seat 12 of the hanger, but its inner end is gradually rolled in upon itself. Hook 17 is kept steadily under tension and is prevented 70 from working upwards by the engagement of pin or rivet 21 with the tapering edges of slot 20.

Since various sizes of beads are provided on different sizes of gutters, a gradually self-adjusting connection between the "circle" and the bead 75 attaching means is of considerable advantage. When lever 15 is in its closed position, hook attaching member 17 is in its final, bead engaging stage and is to be held in this relation to the circle for preventing the dislocation of the gutter. 80 If by accident a pressure is exerted against the gutter bead or against its attaching element, the latter must not yield. For this reason angle member 23 is connected to rivet 16 and is so arranged as to adjust itself to the position of attaching 85 element 17, and to hold the latter, when in bead-attaching position, against further movement towards the trough, or what may be termed "inwards."

Referring to Figures 3, 4 and 5, there is shown 90 again a "circle" hanger 10' provided with the usual hook end 11', and a bead seat 12', adapted to support and facilitate the rolling up of bead 13' of gutter 14'.

The attaching element in this figure comprises 95 a hook-shaped member 26, having a hook-end 27 and an attaching end 28, the latter provided with a slot 29, and a corrugated or toothed surface, indicated at 30.

The purpose of the teeth is primarily for enabling the setting of the bead attaching element to different positions relative to the "circle", depending upon the size of bead or gutter to be engaged. In "circle" 10' there is provided a bolt 105 31, having head 32, at the lower surface of which 105 a pair of teeth 33 are provided, adapted to register with corrugations 30 of attaching end 28.

The engagement of the attaching element is accomplished by swinging the hook member from its dotted-line position to its solid-line position, 110

shown in Figure 3, until bead 13' is drawn down sufficiently, so as to properly rest against seat 12', whereafter the hook is pulled or forced down, and bolt 31 is caused to engage with its teeth the corrugations 30, in which position it is tightened.

In order to prevent hook member 26 from moving inwards, I have provided an angular member 34 pivotally attached at 35 to circle-end 11'. This stop 34 is sufficiently strong to allow a ladder to be placed against the gutter bead, or the attaching element itself, without fear that the latter will be displaced from its set position.

Referring to Figure 6, there is shown a modified form of my attaching element which is somewhat simpler than the previously described construction. There is again shown a "circle" 10' provided with a hook-shaped end 11', and a bead seat 12''. Passing through the circle there will be seen a lower pin 36 and an upper pin 37. The former is intended to engage bead attaching element 38, while the upper pin serves as stop or limiting means against the movement of the attaching element in inward direction.

The bead attaching element in this case comprises an upper hook-shaped end 39 and a lower attaching end 40, which latter is provided with a plurality of cut-outs 41 so arranged as to permit pin 36 to pass into one of its cut-outs, while being pulled downwards, in the direction indicated by arrow I, and to engage the lower surface of the cut-out, when the element is in bead-engaging position, shown in full lines. When the hook is pulled down and shoved against the circle, as indicated by arrow II, the bead of the gutter is compressed and rolled up. The moment pin 36 engages the lower edge of one of the cut-outs, and the hook is released, the bead partially unrolls and puts the hook under tension, which keeps it in fixed engagement with pin 36.

The modification shown in Figure 7 illustrates a double attaching element 42, having two hook-shaped upper ends 43, joined at 44 together in a channel form, from which extend downwardly, at 45, engaging ends 46 provided with a plurality of apertures 47. The apertures are intended to be engaged by a bolt 48 projecting from both sides of a "circle", indicated at 49, and provided with nuts 50.

This modified form is primarily designed for the purpose of affording a greater bearing surface between hooks and bead, and also for enabling a greater manual pull to be exerted against the trough. The two attaching ends 46 allow more than one person to pull down the hooks simultaneously, if need be. Once the attaching element is moved to its desired position, bolt 48 may be either slipped through circle 39, or when it is already secured thereto, two corresponding holes of flaps 46 are passed over the bolt ends.

While I have shown specific constructions of my device, be it understood that modifications and improvements may be made therein without departing from the principal idea of ready-made adjustable bead attaching elements in connection with gutter hanger circles, and I therefore reserve for myself the right to make such changes and improvements as may become necessary in course of the practical application of my device in the trade.

I claim:

1. The combination with a "circle", of gutter bead attaching means, comprising a hook-shaped stamping having a dependent attaching end provided with means for adjusting it relative to said "circle" for different sizes of gutters, said attaching means having provisions for engaging a holding member provided with said circle and disposed transversely to the plane of said hook-shaped stamping.

2. The combination with a "circle"-type gutter hanger, of an adjustable gutter bead attaching means, having a hook-shaped upper end adapted to engage the bead of a gutter, a lower end in engagement with said circle, said lower end having provisions for setting and fastening it in desired position relative to said circle for accommodating various sizes of gutters, and holding means provided with the hanger transversely to the plane of said bead-attaching means and adapted to be engaged by the lower end of the latter.

3. The combination with a "circle"-type gutter hanger, of a gutter bead attaching element, comprising a stamping having an upper hook-shaped end and an attaching extension, the latter having a series of adjusting provisions adapted for setting and holding the stamping in desired position and in engagement with the bead of a gutter supported by the hanger, holding means transversing the gutter hanger and adapted to be engaged by said adjusting provisions of the attaching extension.

4. The combination with a "circle"-type gutter hanger, of a gutter bead attaching element, comprising a stamping having an upper hook-shaped end and an attaching extension, the latter having a series of adjusting provisions adapted for setting and holding the stamping in desired position and in engagement with the bead of a gutter supported by the hanger, a pin member in engagement with said adjusting provisions and adjustable means provided with said hanger for limiting the movement of the upper end of the element in the direction towards the gutter.

5. The combination with a "circle"-type gutter hanger, of a gutter bead attaching element having a hook-shaped upper end and an adjustable lower end, and adjustable means secured to said hanger and cooperating with said element, for limiting the inward movement of the latter, said means extending transversely to and from the web of the hanger and adapted to conform with the position taken by said attaching element.

6. The combination with a gutter hanger of the "circle"-type, of a gutter bead attaching element secured thereto and comprising a stamping having a hooked-shaped gutter bead engaging portion and an extension, the latter provided with corrugations and a slot, a bolt member in engagement with said "circle" and said slot of the engaging portion, said bolt provided with means for engaging one of said corrugations in fixing the element in desired position relative to the "circle".
